UNITED STATES PATENT OFFICE.

LEONARD WELDON, OF COHOES, NEW YORK.

APPARATUS FOR DYEING WOOL.

SPECIFICATION forming part of Letters Patent No. 415,930, dated November 26, 1889.

Application filed January 25, 1889. Serial No. 297,523. (No model.)

To all whom it may concern:

Be it known that I, LEONARD WELDON, of Cohoes, in the county of Albany, in the State of New York, have invented new and useful 5 Improvements in Wool-Dyeing Machines, of which the following, taken in connection with the accompanying drawings, is a full, clear, and exact description.

This invention relates to appliances which, 10 although adapted for dyeing warps and skein-yarn, are more specially designed for dyeing carded or combed wool in the form of slubbing or wool tops.

The object of the invention is to dye the 15 slubbing uniformly and at the same time maintain the fibers thereof in that parallel position in which they are placed by the combing-machine, and to also prevent said slubbing from matting during the dyeing process, 20 and thus obviate the necessity of recombining the same before spinning it into yarn, as has been customary in most cases heretofore; and to that end my invention consists in the novel 25 construction and combination of the components of the dyeing apparatus, as hereinafter fully described, and specifically set forth in the claims.

In the annexed drawings, Figure 1 is a front view of an apparatus embodying my invention. Fig. 2 is a vertical transverse section of the same with only a portion of the supplemental frames or cylinders connected to the main or dipping frame or cylinder and illustrating the pivotal bearings for the former on the latter. Fig. 3 is an enlarged detached side view and partly longitudinal sectional view of one of the supplemental cylinders. Fig. 4 is a transverse section of the same, and Fig. 5 is a transverse section of 35 the latter with the slubbing applied thereto and enveloped in a porous or perforated wrapper.

Similar letters of reference indicate corresponding parts.

45 A represents the vat containing the dye-liquor; and B denotes the dipping-frame, which is arranged to move partly in and partly out of said vat, and may be of any suitable form, preferably composed of two 50 heads or end plates secured at their centers to a shaft *a*, which is journaled horizontally

in suitable bearings in the top of opposite ends of the vat and has secured to one of its ends a driving-pulley or gear-wheel *b*. The inner side of each of said heads is provided 55 with a series of sockets or bearings *c c c*, arranged, preferably, in a circle concentric with the shaft *a* and of any suitable form to permit the attachment and detachment of the supplemental frames or cylinders C C C, 60 which are extended lengthwise of the dipping-frame B and have their shafts pivoted at opposite ends in the aforesaid bearings of the two heads of the dipping-frame.

The supplemental frame C, I prefer to form 65 of a perforated sheet metal cylindrical body secured at opposite ends to annular heads *h* *h* of greater diameters than the aforesaid body, so as to form circumferential flanges thereon. Said heads are provided with openings *e e* at their centers for the admission of dye-liquor to the interior of the perforated cylinder, said openings being preferably of smaller diameter than the body of the cylinder, so as to form on the ends of the latter 70 inward-projecting flanges *p*, which serve to retain a portion of the dye-liquor in the said cylinder as the same passes out of the vat. One or both ends of each supplemental frame or cylinder C has cams *l l* projecting from its 75 periphery, and in the path of said cams is a detent *n*, secured to a suitable support attached to the vat A.

In connection with the supplemental frames or cylinders C, I employ porous or perforated 80 wrappers *d d* in the manner and for the purpose hereinafter explained.

The operation of my improved dyeing apparatus is as follows: The wool combing or slubbing is wrapped evenly around the supplemental frame or cylinder C while removed from the dipping-frame A, and after a sufficient quantity is thus applied a covering *d*, of wire-cloth or other suitable porous or perforated material, is wrapped around the afore- 95 said wool combing or slubbing and secured thereto, and then the frames or cylinders C thus prepared are inserted into the dipping-frame B and mounted in the bearings *c c* thereof. After the desired number of the 100 frames C are introduced into the dipping-frame the latter is set in motion, and in its

rotation it carries the supplemental frames or cylinders C C successively into and out of the dye-liquor in the vat. In passing through the said liquor the wrapper *d* enveloping the wool 5 combing or slubbing protects the same, so as to prevent it from becoming matted on the outside. At the same time a portion of the dye-liquor enters the interior of the supplemental frame of cylinder C through the open 10 ends thereof, and in the passage of said frame or cylinder C over the top of the vat the dye-liquor contained in the supplemental frame or cylinder C drains through the wool combing or slubbing on the bottom of said frame 15 or cylinder, while the dye-liquor on the outside of the wool combing or slubbing carried on the upper part of the frame or cylinder C drains to the interior of the latter, and in passing the detent *n* the supplemental 20 frame or cylinder C receives a partial rotation independently of the main cylinder or dipping-frame B, and thereby causes different portions of the supplemental frame or cylinder C to be carried above and beneath 25 the axis thereof. Said change of the position of the peripheries of the supplemental frames in relation to the axis thereof, together with the drainings of the dye-liquor in opposite directions through the wool combings or 30 slubbing, causes the same to be effectually and uniformly dyed.

What I claim as new, and desire to secure by Letters Patent, is—

1. An apparatus for dyeing slubbing or 35 wool tops, comprising a dye-vat, a dipping-frame arranged to move partly in and partly out of said vat, supplemental frames in said dipping-frame, adapted to carry wrapped around them the articles to be dyed, and porous 40 wrappers adapted to be folded around said articles carried on the supplemental frames, as set forth.

2. In combination with the dye-vat and dipping-frame pivoted horizontally and arranged partly in the vat, perforated hollow 45 frames each adapted to carry wrapped around its exterior the articles to be dyed, having openings in its ends and so arranged that it

may be reversed in its bearings independently of the others in the dipping-frame, as 50 set forth.

3. An apparatus for dyeing wool tops, consisting of a dye-vat, a dipping-frame pivoted horizontally near or on top of the vat, carrying perforated hollow cylinders each adapted 55 to carry wrapped around its exterior a layer of tops, and having open ends and supported in the dipping-frame, as and for the purpose set forth.

4. An apparatus for dyeing wool tops, composed of a dye-vat, a rotary dipping-frame arranged partly in said vat, perforated hollow cylinders carried in the dipping-frame and each of said cylinders adapted to carry wrapped around it a layer of wool tops, and 65 porous wrappers adapted to be folded around the wool tops carried on the said cylinders, substantially as and for the purpose set forth.

5. In an apparatus for dyeing slubbing or wool tops, the combination of the vat A, frame 70 B, dipping in said vat, the cylinders C C, carried in the said dipping-frame, and each of said cylinders composed of a perforated sheet-metal body and of heads *h h*, provided with openings in their centers, and porous 75 wrappers applied, respectively, to the, slubbing or wool tops wrapped around the cylinders, substantially as described and shown.

6. In an apparatus for dyeing slubbing or wool tops, the combination of the vat A, frame 80 B, dipping in said vat, the cylinder C, arranged in said dipping-frame and composed of a perforated sheet-metal body, and of heads *h h*, of greater diameters than the body and provided with openings in the centers of 85 the heads, substantially as described and shown.

In testimony whereof I have hereunto signed my name, in the presence of two witnesses, at Cohoes, in the county of Albany, in the State 90 of New York, this 21st day of January, 1889.

LEONARD WELDON. [L. S.]
